UNITED STATES PATENT OFFICE.

ARTHUR H. DODGE, OF NEW YORK, N. Y., ASSIGNOR TO THE J. G. WILSON CORPORATION, OF NEW YORK, N. Y., A CORPORATION OF VIRGINIA.

MOVABLE DOOR BINDER.

Application filed December 17, 1923. Serial No. 681,172.

This invention relates to doors and is particularly intended to be used with sliding doors of the fire resisting type. Such doors are usually hung on rollers which travel along a track from open to closed position in which the door overlaps the edges of the doorway it is designed to close. During a fire, great differences in temperature and air pressure frequently exist on opposite sides of the closed fire door, tending to force the door away from the wall at points which are not firmly secured thereto, or even to buckle the door between such points. In either event, the fire goes through the opening and the protective usefulness of the door is destroyed.

The object of my invention is to provide a door construction which shall be more secure against such failure to protect than previous doors have been. The provision of binders on the wall to hold the front edge of the closed door has been known, also that the overhead rollers will secure the top edge to the wall, but the rear edge of the door has been the weak spot, often being left entirely free to be forced away from the wall during a fire.

An important object of my invention is to provide means for binding the rear edge of the door to the wall. Such binding means cannot be permanently placed, as they would interfere with free opening and closing of the door. I therefore make the rear edge binders movable, and provide means responsive to closing movement of the door to operate the binders to interlock the rear edge of the door and the wall. Conversely, to prevent interference of the movable binders with the normal free sliding movement of the door, I provide means responsive to initial opening movement of the door to disengage the movable binders from the wall and to hold them unlocked while the door is at all open. By this feature I positively avoid the danger that anyone should be locked in a burning compartment.

In the drawings illustrating one of the many possible embodiments of the invention, Fig. 1 is a front elevation of one type of fire door equipped with the binders of my invention;

Fig. 2 is a horizontal section on a larger scale, on the line 2-2 of Fig. 1;

Figs. 3 and 4 are horizontal sections, with

parts broken away, on the line 3-3 of Fig. 1, Fig. 3 showing the door closed and the binder operated, while in Fig. 4 the door is not quite closed and the movable binder is in normal position;

Fig. 5 is a vertical sectional detail on the line 5-5 of Fig. 3, showing the movable binder at the rear edge of the door;

Fig. 6 is an elevation with parts broken away of a different type of door equipped with movable binders; and

Figs. 7 and 8 are respectively vertical and horizontal sections taken on the lines 7-7 and 8-8 of Fig. 6.

Referring to Figs. 1 to 5, a wall 9 has a doorway 10 with a fire resisting door 11 to close it in case of fire. The door has a frame made up of the channel members 12 joined together as by welding at the four corners. Spaced reinforcing channels 13 extend vertically between the top and bottom channels, and one or more diagonal tie rods 14 make the frame a rigid unit. The frame is sheathed by the horizontally extending sheets 15 which are lapped over the edges of the channel frame members and firmly united thereto as by spot-welds.

Above the doorway is a track 16 upon which the door is hung by means of hangers 17 having rollers 18 grooved to travel on the track. The track may be horizontal or inclined; in the present example it is shown as inclined so as to close the door when released from its open position in which it is held by a chain 19. The chain extends from a bracket 20 at one edge of the door, over a sheave 21, and carries suitable counterweights 22. The chain includes the usual link 23 which fuses in case of fire to release the counterweights and thus permit the door to travel down the track into its closed position. The movement into closing position may be limited by any suitable abutment, but I prefer to use binders 24 secured to the wall, as by expansion bolts 25, in a position to limit travel of the door. Each binder has the usual offset portion 26 which overlies the inner flange of channel 12, constituting the front edge of this type of fire door. The binders thus interlock the front edge of the door and wall and positively prevent movement of said front edge away from the wall.

The bottom of the door is prevented from

movement at right angles to the wall by the usual bracket 27 carrying a roller 28 which rests against the lower rear corner of the door when closed, and by the lowermost binder 5 at the front edge of the door. The full length of the door between the roller and the hanger nearest the rear edge of the door has ordinarily been left without means for securing it to the wall, and it is obvious 10 that when a fire starts on one side of the door, the space on the other side maintains its normal temperature and pressure, while the fire changes both and may produce such a great inequality of conditions on 15 opposite sides of the door as to bulge out or buckle the rear edge of the door, even when the frame is of the most rigid construction. I, therefore, provide at least one movable binder at the rear edge of the door intermediate 20 the top and bottom edges and means for operating this binder to interlock the rear edge of the door and the wall when the door is closed. For high doors I prefer to use three binders, shown as the hook-shaped catches 29 which are fast on the vertical shaft 30. The shaft 30 is journalled for rotation in suitable brackets 31 secured to the channel 12. At the side of the doorway adjacent the rear edge of the door when 25 closed, I cut out recesses in position to receive the catches 29 when operated, and cover the recesses with the apertured anchorage plates 32. The central movable binder, located at about the midpoint of the rear edge of the door, is held fast to shaft 30 by a pin 33 which extends somewhat beyond the surface of the catch but not enough to strike the channel flange when the shaft is 30 rotated. The other catches when used are rigidly mounted on the shaft as by set screws 34.

To operate the movable binders in response to closing movement of the door, I preferably provide an operating bar 35 which has an opening 36 near one end in which the projecting portion of pin 33 is seated. The bar 35 extends transversely of the door, it being slidably in apertures 37 in the frame members and reinforcing channels 40. The front end 38 of the operating bar is bent over beyond the web portion of the front edge channel 12 into position to abut the offset portion 26 of one of the binders 24. In construction having spaced frame members covered by sheathing plates, such as shown, the operating bar passes within the door between the sheathing plates, so that no change is made in the appearance of the door and there is no likelihood of the 50 movable binder operating mechanism being tampered with or otherwise damaged.

When the link 23 fuses and the door moves down the track to its closed position, the end of the stationary binder 24, opposite 55 the bent-over end 38 of the operating bar,

strikes the operating bar and moves it from the position shown in Fig. 4 (just before the door is fully closed) into the position shown in Fig. 3. This movement of the operating bar moves the pin 33 and thus rotates the 70 shaft 30 in a clockwise direction and swings the hook portions 39 of the movable binders into interlocking engagement with their respective anchorage plates 32. Obviously, it is impossible to move the rear edge of the 75 door away from the wall while the movable binders are in engagement with the anchorage plates.

In order to permit free movement of the door along the track independently of the condition of operation of the movable binders, I prefer to provide means responsive to opening movement of the door for disengaging the catches 29 from their anchorages. In the present instance I have shown a 80 spring 40 coiled about the shaft 30, having one end fast to the shaft and the other end secured to one of the journalling brackets 31. The tension of the spring is such as to rotate the shaft in an anti-clockwise direction 85 whenever the pressure of the stationary binder 24 is removed from the operating bar 35. A pin 41 in the bracket 31 acts as a stop for the shaft pin 33 to limit such binder retracting movement of the shaft 90. The apertures in the anchorage plates 32 are made wide enough to give ample clearance to the hooked ends 39 of the movable binders 29 as opening movement of the door 95 is begun. It will be apparent that opening 100 of the door is as free with my movable binder construction as it would be without such equipment.

In Figs. 6, 7 and 8 I have shown my invention applied to a fire door of somewhat different construction. As the general principle is the same as in the construction previously described, I have designated similar parts with like reference characters and need only describe the specific differences between the constructions. The door 42 has an outside frame made up of the T-rails 43, which are beveled at their ends and firmly united either by welding or by the gusset plates 44, or both. The reinforcing channels 45 are centrally slotted at opposite ends to receive the web portions of the frame rails 43. The reinforcing channels are positioned in parallel vertical relation at suitable intervals, and are secured to the top and bottom frame rails by bolts or rivets 46 which pass through registering holes in the flange portion of the reinforcing channels and the web portion of the frame rails. The door hangers 47 carry the usual rollers 48, but are bent over at their lower ends to form the attaching plates 49 which are secured directly to the edge of the frame rail by welding, or otherwise. The sheathing plates 50 on the side of the door towards the 110 115 120 125 130

wall are lapped around the edges of the frame rails, the edges of the sheaths being crimped over, as shown at 51. The opposite sheathing plates 52 pass completely around the edges of the door, and are secured by rivets or bolts 46 to the reinforcing channels 45 nearest the front and rear edges, respectively, of the door.

In this construction the stationary binders 53 must be offset sufficiently to overlap the entire thickness of the door, so that they grip the surface of the door opposite the wall instead of the inner flange of the channel frame, as in the previously described construction. The brackets 54 have vertical angle portions which are secured directly to the rear edge of the door outside the sheathing. In this construction also, the operating bar 35 is housed within the door between the sheathing sheets. The movable binders and their operating mechanism are similar to those already described, but the specific shape of the catches 55 must be slightly different from the catches 29 in order correctly 25 to engage the anchorage plates 32 as seen most clearly in Fig. 8.

While I have described my invention as applied to two types of fire doors, it is obvious that they are applicable to all types of fire doors which slide along a track between open and closed position. In some cases the operating bar might not be housed within the door; for example, if the door were solid. While three stationary and three movable binders have been shown, it will be apparent that any desired number may be provided without changing the operation of the binders. In case only one movable binder is employed, it should be located about halfway between the top and bottom edges, and the shaft 30 becomes a short pin. With this construction, the catch 29 need not be affixed to the shaft so long as it is movable with the pin 33, but the spring 40 should always be arranged to interconnect some part movable with the catch and some fixed portion of the door, so as to retract the movable binder when the door is at all open. Other changes in detail will suggest themselves to those skilled in door construction, without in any manner departing from the spirit of the invention.

What I claim as new is:

1. In door construction, a wall having a doorway, a sliding door to close the doorway having an edgewise movement of translation only, a fixed abutment, and means operated by engagement with the abutment to bind the rear edge of the door to the wall in response to closing movement of the door.
2. The combination with a door slidable to close a doorway in a wall and a binder on the wall to engage one edge of the door when closed, of a binder on the door at its opposite edge, and means responsive to engagement

of the first binder and the door for moving the other binder into engagement with the wall.

3. In door construction, a wall having a doorway, a sliding door to close the doorway, a movable door binder for binding the rear edge of the door to the wall when the door is closed, and means for controlling and actuating the binder to leave the door at all times free to slide the door binder imposing no frictional resistance to the movements of the door at least during the greater part of the opening and closing movements.

4. In door construction, a wall having a doorway, a sliding door to close the doorway, a catch pivoted at the rear edge of the door for movement towards the wall, an anchorage on the wall in position to be engaged by the catch when the door is closed and the catch operated, a catch operating member extending beyond a portion of the front edge of the door, and an abutment in the path of movement of the operating member to actuate the same as the door slides into closed position.

5. In door construction, a wall having a doorway, a sliding door to close the doorway, a catch on the rear edge of the door, an anchorage member on the wall, catch operating means housed within the door to move the catch into engagement with the anchorage member, and a member on the wall to actuate the catch operator as the door closes.

6. In door construction, a door adapted for sliding movement relative to a wall to close a doorway therein, a hook shaped catch rotatably mounted at one of the side edges of the door and adapted to engage an anchorage in the wall, an operating bar extending from the catch across the door and projecting beyond part of the opposite side edge of the door, and means connecting the bar and catch, whereby movement of the bar towards the catch will rotate the same to engage an anchorage in the wall when the door is mounted next to a wall having an anchorage.

7. In door construction, a door adapted for sliding movement relative to a wall to close a doorway therein, a hook shaped catch mounted at one side edge of the door for rotation about an axis parallel to said edge, a spring urging said catch to rotate away from the wall, and an operating bar connected to the catch and extending transversely of the door beyond the opposite edge thereof, said bar being adapted to be pushed by a member projecting from the wall as the door closes, and thereby to move said catch into engagement with an anchorage on the wall, and said spring restoring the catch and bar to normal position when the member ceases to push the bar.

8. In door construction, a wall having a doorway, a door comprising a frame and

- spaced sheathing plates secured to opposite sides of the frame, means for supporting the door for sliding movement to close the doorway, a binder on the wall to grip the front edge of the door when closed, an anchorage on the wall adjacent the rear edge of the door when closed, a movable binder on the door to engage the anchorage, and means housed between the opposite sheathing plates 5 in position to be actuated by the wall binder to operate the movable binder as the front edge of the door closes against the wall binder.
9. In door construction, the combination 10 with a wall having a doorway, a door movable to close the doorway, a plurality of spaced binders on the wall at one side of the doorway in position to engage the front edge of the door when closed, a rotatable shaft extending along the rear edge of the door, a plurality of spaced anchorages on the wall at the side of the doorway opposite the binders, a plurality of hook shaped catches fast on the shaft and in position to engage the anchorages when the door is 15 closed and the shaft rotated, and means for rotating the shaft as the door moves into closed position.
15. In door construction, the combination 20 with a wall having a doorway, a door movable to close the doorway, a plurality of spaced anchorages on the wall at the side of the doorway opposite the binders, a plurality of hook shaped catches fast on the shaft and in position to engage the anchorages when the door is 25 closed and the shaft rotated, and means for rotating the shaft as the door moves into closed position.

Signed at New York, New York this 11th day of December 1923.

ARTHUR H. DODGE.
